[57] CLAIM

The ornamental design for a respiratory protection scarf, as shown and described.

DESCRIPTION

FIG. 1 is a elevational front view of a respiratory protection scarf showing my new design;

FIG. 2 is a rear elevational view thereof;

FIG. 3 is a front perspective view in a folded position; and,

FIG. 4 is a side elevational view thereof.

The crosshatch shading in FIGS. 1 through 4 is understood to repeat throughout the indicated area.

FIG. 3.

FIG.4.
